[57] CLAIM

The ornamental design for a base for a mobile home support stanchion, as shown and described.

DESCRIPTION

FIG. 1 is a top plan view of a base for a mobile home support stanchion showing my new design;

FIG. 2 is a right side elevational view thereof;

FIG. 3 is a bottom plan view thereof; and,

FIG. 4 is a front elevational view thereof.

The left side elevational view is a mirror image of the right side elevational view. The rear elevational view is a mirror image of the front elevational view.
